UNITED STATES PATENT OFFICE.

CHERUBINO MONTAGNA, OF CECIL, PENNSYLVANIA.

SPRING FOR DOORS.

Application filed May 17, 1921. Serial No. 470,396.

To all whom it may concern:

Be it known that I, CHERUBINO MONTAGNA, a subject of the King of Italy, and resident of Cecil, in the county of Washington and 5 State of Pennsylvania, have invented certain new and useful Improvements in Springs for Doors; and I do hereby declare the following to be a full, clear, and exact description of the invention, such as will enable 10 others skilled in the art to which it appertains to make and use the same.

The invention consists in certain novel features and details of construction as will be more fully described hereinafter and 15 finally pointed out in the claim.

In the drawings, Figure 1, is a side elevation of a door and frame showing my improved spring attached thereto.

Fig. 2, is a plan view of the spring 20 detached. Fig. 3, is a detail view of the ratchet-wheel and pawl. Fig. 4, is a detail view of the guide or protecting plate, and Fig. 5, a rear edge view showing in detail the bolt 25 for holding the arm or lever back in position when not in use.

Similar letters of reference indicate corresponding parts in the several figures of the drawings.

A, represents a door, B, the frame thereof 30 and C, the main plate into which are secured the several parts comprising my invention.

The plate C, is provided with lugs or shoulders D, and E, near each end thereof for receiving the ends of a pin F, around 35 which is coiled a spiral spring G, the construction of which will be more fully described hereinafter.

Secured on the pin F, at or near the center thereof is an arm or lever H, which is slotted 40 at the rear end for receiving a tongue formed on the spring G, near the center thereof and is also slotted at or near the outer end and provided with a revolving disc or wheel I, which forms a bearing which is adapted to 45 engage in a groove or recess J, in a plate K, which is secured on the face of the door A, the purpose of which is to prevent the disc or wheel from scarring the door.

As will be seen, a small ratchet-wheel L, 50 is secured on the upper end of the pin F, which is adapted to be engaged by a pawl M, which is secured on the lug D. This

ratchet-wheel has holes N, drilled or formed in it at the front end of each tooth, the purpose of which is to receive a small pin O, 55 for turning the ratchet-wheel L, which causes or produces the tension on the spring G, and arm or lever H.

The spring is formed by starting in the center leaving what might be termed a 60 tongue or projection P, and is coiled from the center out. The lower end of the spring is secured to the lower end of the pin F, and the upper end is secured in or to the under 65 side of the ratchet-wheel L, and the tongue or projection P, is inserted in a slot or groove in the rear end of the arm or lever H.

The main pin F, is then run through said spring G, arm or lever H, and ratchet-wheel L, after which it is secured in the lugs or 70 shoulders D, and E.

The back edge of the plate C, is turned up and is provided with a small bolt R, for fastening the arm or lever H, back out of 75 engagement with the door when so desired.

Retaining lugs are also formed on or in the plate C, for holding a pin O, which is used for turning up the tension on the spring G.

The spring proper is attached to the door 80 frame B, by means of screws, and the plate K, secured to the stile of the door by the same means.

By removing the pin O, from the retainers S, and inserting the same into the holes in 85 the ratchet-wheel L, any desired tension may be put on the arm or lever that may be desired.

Having described my invention, what I 90 claim and desire to secure by Letters Patent is:

A new article of manufacture, in the nature of a door spring, comprising a plate which is provided with lugs or shoulders 95 which are adapted to receive and hold the ends of a pin, a ratchet-wheel secured to the upper end of said pin, a pawl pivotally secured to the upper lug or shoulder and engaging with said ratchet-wheel for holding same after the tension has been put on, retaining lugs formed in or on said plate for holding a pin for turning said ratchet-wheel, a bolt on the back edge of the plate for holding the arm or lever out of engagement when 100

not in use, together with an annular plate adapted to be secured to the door for receiving a disc or wheel in the end of the arm or lever, all substantially as shown and for the purposes described.

In testimony that I claim the foregoing as my own invention, I have hereunto set my

hand in the presence of two subscribing witnesses.

CHERUBINO MONTAGNA.
